UNITED STATES PATENT OFFICE.

ALBERT WORCESTER, OF LOS ANGELES, CALIFORNIA.

BOX-COVERING MACHINE.

Application filed September 1, 1922. Serial No. 585,649.

To all whom it may concern:

Be it known that I, ALBERT WORCESTER, a subject of the King of Great Britain, residing at Los Angeles, in the county of Los Angeles and State of California, have invented new and useful Improvements in Box-Covering Machines, of which the following is a specification.

This invention relates to box covering machines, and particularly to that type of machine in which a box body is continuously rotated while there is applied to the same a continuous covering strip or sheet, this being cut off at the suitable moment during the box covering operation.

An object of the invention is to provide a semi-automatic power driven machine whereby a rotating box body is enveloped on its peripheral faces with a suitable covering and means are included for effecting the severing of the covering sheet at the proper moment. An object is to provide in a machine of this character a safety device or mechanism in which the possibility of the fingers 25 of the operator being cut or severed is materially reduced. Another object is to provide a cutting means which may be operated at suitable intervals by power driven mechanism or which can in cases of necessity be 30 manually operated.

Another object of the invention is to provide in a box covering machine an adjustable demountable box form arm, provision being made for adjusting the length of the 35 arm and for adjusting the lateral position of the box form on the arm with respect to the machine.

Another object of the invention is to provide means for facilitating the relative adjustment of the movable cutter of the machine with respect to the stationary support.

A further object of the invention is to provide in a box covering machine means for varying the speed of the operating mechanism according to the size of box being covered.

Other objects and advantages will be made manifest in the following specification of an embodiment of the invention shown in the accompanying drawings, wherein

Figure 1 is a side elevation of the improved machine;

Figure 2 is a perspective of the cutting head;

Figure 3 is a vertical section from front to rear through the cutting head and show-

ing a movable cutter member in elevated position;

Figure 4 is a side elevation and partial vertical section of the cutter operating mechanism showing the cutter in its cutting-off position;

Figure 5 is a face or end view of the cutter operating coordinate levers;

Figure 6 is a side elevation showing the cutter levers in the forward or cutter opening position;

Figure 7 is a side elevation of a secondary counter shaft showing the speed varying mechanism and the clutch thereon;

Figure 8 is a plan showing the adjustable demountable box form arm;

Figure 9 is a side elevation of the demountable arm;

Figure 10 is a sectional detail view showing the arm slide clamp.

In machines of the kind forming the subject matter of the present invention, a strip of paper P is drawn from any suitable reel R over a gumming roller 2 arranged in a suitable basin 3 at the rear end of the machine and which is here shown as including a suitable frame 4. At the front end of this frame there is provided a substantially fixed transversely extending bed plate 5, the ends of which are attached to brackets 6, and these extend forwardly from a cross frame 7, Figure 3, which is mounted upon the principal frame structure 4.

The gummed paper passes down over the front of the bed plate 5 and is adapted to wrap about the box body which is carried upon a rotating form F. During the operation of the machine, the paper is intermittently cut after a suitable length has been applied to the box body and this cutting is effected preferably by a swinging and yieldingly operative means, so that in case of accident if the fingers or hand of the operator should be caught between the bed plate 5 and the cooperating cutter 10, the latter would stop, owing to the presence of the obstruction, and thus prevent injury to the operator.

The cutter operating means is shown as including a cutter beam 11 extending transversely of the machine and being pivotally mounted along its upper longitudinal edge on a pivot device 12. The pivot device 12 of the cutter beam 11 is mounted in a swinging carrier having side arms 13 and a transverse web 14 through which passes a bolt 15

which also passes through the cutter beam 11, the bolt providing for the adjustment of the beam toward and from the carrier web 14. There may be one or more of the bolts 5 as necessary, and threaded in the web 14 is one or more jack and adjusting screws 16, the heads of which support the contiguous beam 11. The jack screws 16 and the bolts 15 therefor provide for the accurate adjustment and positive locking of the cutting blade 10 with respect to the fixed bed plate 5. The web 14 has cushions 14' to engage the plate 5.

The carrier frame 13 has downwardly extending arms 13 $\frac{1}{2}$, and these have bosses, one of which is mounted on a trunnion or bearing pin 17. The other bearing arm 13 $\frac{1}{2}$ is provided with a downwardly extending lever arm 18 and this is connected to the upper end of a drive rod 19 which is pivotally and adjustably connected at 20 to a lever 21, which is secured as by a set screw 22 on a rock shaft 23. The rock shaft is mounted in bearings 24 on the front end of the main frame 4. The rock shaft is oscillated at suitable intervals by a power mechanism which is under the control of the machine operative and the actuating mechanism includes a lever arm 25, Figures 5 and 6, which is loosely mounted on the rock shaft 23 and is held between a set collar 26 and the hub 27 of a finger 28, the latter being fixed as by a set screw 29 on the rock shaft 23. The upper swinging end of the loosely mounted lever 25 is slotted at 25 $\frac{1}{2}$ and receives a pin 30 provided on the forward end of a shank 31 of a driving yoke 32 which straddles and is supported upon a shaft 33 disposed transversely of the frame 4 and somewhat back of the front legs thereof. The shaft 33 is provided with a fixed cam 34 having a concentric peripheral portion 34 $\frac{1}{2}$ and a depressed portion 34 $\frac{1}{2}$, and the yoke 32 is provided with a cam roller 35 drawn constantly against the periphery of the cam 34 by suitable means, preferably consisting of a tension spring 36, one end of which is attached to the yoke 32 and the other end to any suitable fixed part on or of the frame and which may consist of a bracket 37. From this it will be seen that the yoke 32 is positively actuated by the cam in the forward movement of the yoke, the shank end of which is supported in a guide 38 fixed to the frame and during the rotation of the cam 34 the yoke 32 is pulled back by the contraction of the spring 36. This yielding or retracting movement of the yoke 32 is utilized in the present machine through suitable connections to throw the carrier 13 with the cutter 10 in its downward stroke to sever the strip of paper P.

When the lever arm 25 is in its retracted position, Figure 4, a gravity actuated pawl 40 hangs in a downwardly extending oblique

position and rests upon a bracket 41 fixed to the machine. This pawl is arranged on one side of the lever arm 25 and is connected to a rock shaft 42 extending transversely across the lever 25 and on the opposite end of this shaft there is fixed a latch 43 which has a notch 44 in its swinging end that is designed to fall down over a pin or shoulder 28 $\frac{1}{2}$. Figure 6, when the lever 25 is in the rearmost position, Figure 4. The latch receiving pin 28 $\frac{1}{2}$ is formed upon or provided on the upwardly extending lever finger 28 which is secured as by the set screw 29 on the rock shaft 23. When the cam 34 rotates it forces the yoke 32 forwardly out of the cam depression and thus moves the lever arm 25 forwardly from the position shown in Figure 4 to the position shown in Figure 6, and during this movement the latch 43, being connected to the latch pin 28 $\frac{1}{2}$, pulls the finger 28 forwardly until the downwardly curved end of the pawl 40 in riding out on the bracket 41 is lifted and rocks the rock shaft 42 and disconnects the latch 43 from the latch pin 28 $\frac{1}{2}$. It will thus be seen that the rock shaft 23 is initially operated by power when the latch 43 is connected to the finger 28. The forward movement of the lever 25 and its temporarily connected finger 28 results in the downward movement of the lever 21 and by virtue of the connecting rod 19 the cutter frame 13 is swung upwardly, carrying with it the cutter blade 10. During the continued forward movement of the yoke 32 and after the finger 28 is disconnected from the finger 28, the now disconnected frame 13 is moved to its uppermost position by the action of other means, preferably consisting of over-balancing weights 46, ends of which may be pivoted to the frame structure 4, having swinging ends connected as by the chains 47 to the outer ends of the arms of the frame 13. The chains 47 are shown as passing over guide rollers 48 mounted on the head frame. This capacity for the automatic disconnection of the knife carrier 13 from the positively actuating mechanism enables the operative to again readily pull the cutter down by hand if necessary during the operation of the machine to cut paper.

After the cam 34 has rotated to such degree as to thrust the yoke and the lever 25 to foremost position, as shown in Figure 6, the continued rotation of the cam permits the spring 36 to pull the yoke 32 rearwardly as the cam depression 34 $\frac{1}{2}$ is presented to the cam roller 35, and this results in the retraction of the yoke 32 and the lever 35. During the retraction movement, the lever engages the overlapping or contiguous portion of the finger 28 and the rock shaft is thus reversed in direction of operation and the connecting rod 19 is thrust upwardly with the result that the knife carrier 13 and the

knife 10 are swung downwardly in the cutting action, this movement being accomplished by the tension spring 36. This, therefore, enables the knife and the carrier 13 to yield in case of material obstruction to the downward movement the degree of resistance of which is sufficient to prevent the effort of the spring 36 to pull the cutter carrier and cutter down.

10 For driving the shaft 33 this latter is provided with a gear wheel 50, and this engages with a pinion 51 which, in turn, is secured on a shaft 52 mounted in suitable journals 53 provided on the frame. Slidably mounted on the shaft 52 is a disk 54 operative by a shift lever 55 to which is connected a link 56 attached at its lower end to a foot pedal 57. The link 56 is normally pulled downwardly by a contractile spring 58 attached thereto and to a suitable fixed part of the frame. Figure 7. Downward pressure on the pedal 57 results in the shifting of the disk 54 toward a variable speed device, here shown as consisting of a three-stepped pulley 59 loosely mounted on the shaft 52. In the larger end of this pulley there is provided a suitable clutch device or member 60 which is thrown into action by a pin 54₁ attached to the actuating disk 54, and when the clutch member 60 is operatively connected to the pulley 59 this, in turn, drives the shaft 52. The pulley 59 is driven as by means of a belt 62, taking power from the main drive shaft 63.

25 35 The shaft 53 not only serves to operate the countershaft 33, which actuates the cutter mechanism, but the shaft 52 also serves to rotate the box form F.

This box form is mounted upon a shaft 40 64 which is longitudinally adjustable in a gear box 65 in which is arranged a gear 66 splined on the shaft 64 and held in constant engagement with a pinion 67. This pinion is secured on the outer end of a radius shaft 68 mounted in bearings 69 and 70 provided on a radius arm 71 which is slidably adjustable in a guide 72 which has a side wall 73 pivoted on the contiguous end of a fixed, grooved boss 4' bearing the shaft 52. The grooved boss 4' forms, therefore, a trunnion on which the frame 73 can swing and a pin 4^a enters the groove of the boss to fasten the frame in position against axial movement but allows the frame to swing.

45 55 60 Just inside the wall 73 there is fixed on the shaft 52 a pinion 74 and this engages constantly a pinion 75 which is splined on the radius shaft 68 and is prevented from end-wise movement by the contiguous bearing lug 76.

The guide 72, carrying the slide arm 71, has a flat face bearing against a quadrant 77 which is fixed to a portion of the frame 4 of the machine and has a slot 78 in which 65 swings a clamp screw 79 which is threaded

in the contiguous wall or web of the guide 72. This provides for the angular adjustment of the guide 72 about the axis of the shaft 52 and enables the guide to be fastened at any position by setting up the clamp screw 79.

The slide arm 71 is adapted to be extended or retracted by longitudinal adjustment in the guide 72 and is then clamped in desired position by means of a clamp screw 80 passing through the bottom of guide 72 and engaging a clamp member or gib 81 which bears down upon the slide arm 71.

The shaft 64 is longitudinally adjustable through its bearings in the walls of the box 65 and is adapted to be clamped in suitable position by a set screw 82 in collar 83.

From this it will be seen that a form F of proper dimensions may be readily mounted upon the detachable and adjustable radius arm mechanism and the speed of operation of the device may be determined according to the size of the box being covered by changing the speed of the stepped pulley 59, and the box carrying arm can be readily disconnected from its support 4', and other attachments of required characters may be substituted instead.

It is desirable to provide a gradual downward movement of the cutter 10 until it closely approaches the fixed plate member 5. At this position the cutter is given an accelerated movement by the spring 36 as a sharply relieved portion 34₁ in the cam surface moves under the cam roller 35.

Further embodiments, modifications and variations may be resorted to within the scope of the invention as here claimed.

What is claimed is:

1. In a box covering machine, a pivotally mounted cutter carrier, means for pressing the carrier to its effective cutting stroke, means for retracting the carrier, and overbalance weights operative to continue the retracting movement of the cutter carrier when it has been released by the retracting means.

2. In a box covering machine, a pivotally mounted carrier for a cutter and a safety action cutter mechanism whereby the oscillating carrier moves the cutter gradually toward the paper cutting position and then permits the cutter to have a short, free, quick movement for the final period, said means including a cam and a cam-engaging element, the latter being indirectly connected to the carrier and said cam having a rounded shoulder controlling the cutting stroke of the cutter and releasing the cutter for quick, free action only at the final portion of its cutting stroke.

3. In a box covering machine, a driving shaft, a bearing portion surrounding said shaft and including a boss, and an arm car-

- rying device rotatably mounted upon the said boss portion to swing around the axis of the shaft and adapted to be readily attached to and detached from the bearing, and means for locking the arm carrying device against axial movement on the bearing portion but permitting angular movement.
4. In a box covering machine, a pivotally mounted cutter carrier, a fixedly mounted plate member, means for moving the cutter carrier yieldingly toward the fixed plate member, said means including a link and lever train connected to the cutter carrier, a cam having an effective face whereby the cutter carrier moves down gradually to a predetermined position and is then allowed an accelerated final movement, and trip mechanism forming a part of said means.
- 10 5. In a box covering machine, a driving shaft and a form carrying and turning shaft, a hub in which said shaft turns, and a device including a substantially radial arm readily bodily attachable to and removable from the said hub and having means for operatively connecting the driving shaft and the form carrying shaft.
- 15 6. In a box covering machine, a substantially fixed cutter plate and a cutter carrier pivotally mounted as to said plate and means for oscillating said carrier and including an automatic disconnecting trip.
- 20 7. In a box covering machine, a substantially fixed cutter plate, a cutter carrier pivotally mounted as to said plate, means for oscillating said carrier, said means including a cam mechanism for giving an initial opening movement to the cutter carrier and an automatic tripping device to release the carrier, and means for yieldingly swinging the cutter carrier to the cutting position.
- 25 8. In a box covering machine, a substantially fixed cutter plate, a cutter carrier pivotally mounted as to said plate, means for oscillating said carrier, said means including a cam mechanism for giving an initial opening movement to the cutter carrier, and means for yieldingly swinging the cutter carrier to the cutting position, said means including trip means for disconnecting the cutter carrier and the cam mechanism so that the cutter carrier can be independently operated for a cutting stroke.
- 30 9. In a box covering machine, a substantially fixed cutter plate, a cutter carrier pivotally mounted as to said plate, means for oscillating said carrier, said means includ-

ing a cam mechanism for giving an initial opening movement to the cutter carrier, means for yieldingly swinging the cutter carrier to the cutting position, and gravity actuated means for continuing the opening movement of the cutter carrier after its power initiated movement.

10. In a box covering machine, a carrier frame including a transverse portion, a cutter beam pivotally mounted upon the carrier frame, and means for rigidly adjusting the cutter beam as to said transverse portion, said carrier frame being pivoted on an axis along its rear portion and parallel to the cutter member.

11. In a box covering machine, a pivoted cutter carrier having at its front portion a cutting blade, the axis of which is along the rear portion of the carrier, a cam, a link and lever mechanism connected to said carrier, said mechanism being operative by the cam to retract the carrier from the cutting position, and a disconnecting trip in said mechanism.

12. In a box covering machine, a pivoted cutter carrier having at its front portion a cutting blade, the axis of which is along the rear portion of the carrier, a cam, a link and lever mechanism connected to and automatically disconnected from said carrier, said mechanism being operative by the cam to retract the carrier from the cutting position, and means for yieldingly throwing the carrier in the cutting stroke and controlled by said cam.

13. In a box covering machine, a cutter carrier having at its front portion a cutting blade, a pivot, the axis of which is along the rear portion of the carrier, a cam, a link and lever mechanism connected to said carrier, said mechanism being operative by the cam to retract the carrier from the cutting position, and means for yieldingly throwing the carrier in the cutting stroke and controlled by said cam, said connecting means including a trip device whereby the carrier is automatically disconnected from the power actuating means.

14. In a box covering machine, a cutter carrier, a cutter carried thereby, and an operating mechanism connected to the cutter carrier and including a rock shaft, a drive lever fixed thereon, a lever loose thereon, and trip means for connecting said levers.

In testimony whereof I have signed my name to this specification.

ALBERT WORCESTER.
